UNITED STATES PATENT OFFICE

ALBERT LINDBERG, OF CHICAGO, ILLINOIS, ASSIGNOR TO OSCAR HEINEMAN CORPORATION, OF CHICAGO, ILLINOIS, A CORPORATION OF ILLINOIS

CONE FOR THE WINDING OF YARNS AND THREADS

Application filed April 6, 1929. Serial No. 352,999.

This invention relates to cones used in the textile industry for the winding of silk, rayon and other yarns and threads in a form to be used subsequently on knitting machines or whenever and wherever a cone type package is used.

The cone heretofore used for this purpose is a hollow uniformly tapered structure usually of compressed fibre, on which the 10 yarn or thread is wound by rotating the cone at a high speed and coiling the yarn or thread thereon in successive spiral layers until the desired size of cop has been built up.

A trouble heretofore experienced in connection with cones of this type resides in the 15 tendency of the first few coils or windings at the ends of the cone to creep inwardly on the latter and become bunched, instead of retaining the positions in which they were laid 20 during the winding operation. This condition gives a false length of traverse, creating at the end portions of the cone a loose mass 25 of yarn, which is not conducive to good winding, nor to good delivery when the package is unwound.

This tendency is most pronounced at the broad end of the cone; but sometimes occurs also at the narrow end of the cone in the 30 case of cones having a relatively slight taper. This irregularity occurs especially in the coiling of rayon yarns on a cone tube, because rayon is somewhat more springy and 35 wiry than silk or cotton yarn or thread or similar soft fibres.

The object of my present invention is to 40 provide a cone of such a structure that it will overcome the difficulty above-mentioned, and will cause the windings of the yarn or thread to retain permanently, or until unwound, the positions in which they were originally laid on the cone by the winding bar.

My improvement is illustrated in the accompanying drawings, in which—

45 Fig. 1 is an elevation of a cone embodying

my present improvement as applied to the wide or base end of the cone;

Fig. 2 is an axial section of the same;

Fig. 3 is an axial section of a slightly modified form;

Fig. 4 is an axial section of a cone presenting a modified winding surface at both ends, the improvement illustrated in this figure being especially applicable to cones having but a slight taper;

Referring first to Figs. 1 and 2, A designates as an entirety the hollow cone which, as above stated, is usually made of compressed fibre. Heretofore, it has been customary to corrugate, groove or otherwise more or less roughen the exterior surface of the cone to prevent slippage of the yarn or thread thereon. In a cone made in accordance with the present invention, however, this is not necessary, but the exterior surface may be simply the somewhat soft and slightly rough natural surface of the compressed paper pulp or other fibre of which the cone is made; the present invention providing other means for preventing the slipping, creeping or bunching of the yarn on the cone. This means consists essentially in giving to one or both end portions of the external surface of the cone a novel form or shape that will prevent the tendency of the yarn or fibre to creep inwardly and become bunched, as is the case with uniformly tapered cones at the present time. In its broad aspect, the improvement consists in providing the cone tube at one or both ends with a thread-receiving surface that is continuous with the external conical body surface of the tube and extends at an angle inwardly with respect to the conical external body surface. As shown 70 in Figs. 1 and 2, the lower or base portion of the cone designated by B is made externally cylindrical. That is to say, the portion of the external surface of the cone from the bottom up to a point indicated by the 75

80

85

90

transverse line C is cylindrical or parallel with the axis of the cone.

In the form illustrated in Fig. 3, the lower or base portion B' of the external surface of the cone A' is slightly tapered in the reverse direction to the taper of the upper portion of the cone.

In Fig. 4 I illustrate the application of the above principle to both ends of the cone. In 10 this figure I show a cone A'' formed at its wide or base end with an external winding surface B'' that is slightly tapered in the reverse direction to the taper of the intermediate or body portion, and at its upper end 15 with a winding portion D above the line E that has a slightly greater taper than the intermediate portion of the cone but in the same direction. This upper taper D is especially useful on cones having but a small degree of body taper, but is not so necessary on cones 20 having a comparatively substantial taper such as shown in Figs. 1, 2 and 3.

It will be observed that in all the forms 25 illustrated the modified thread-receiving surfaces B, B', B'' and D lie within imaginary extensions of the main tapered external surface of the cone indicated by the dotted lines a, a.

In all of the forms shown, the coils of yarn 30 or thread that are laid on the described end portions of the cones illustrated retained their place and do not slip or work inwardly, so that the yarn or thread is laid uniformly and evenly between the upper and lower limits 35 of the winding area, thus producing a neat looking and uniform product, which gives no trouble from slipping or bunching of the initial layers either in the winding or subsequent unwinding operation. To the securement of 40 this result, the hump formed at the merger of the intermediate and end winding surfaces, represented by the lines C and D, is a contributing factor, for the reason that a layer of yarn will not slip as readily over a humped 45 surface as over a uniform cylindrical or conical surface.

The described end formations of the cone may be created either in the original mold in 50 which the cone is formed by giving to said mold the proper form, or by taking an ordinary uniformly tapered cone and grinding down the external surface of one or both end portions to the desired extent by a suitable abrading machine.

55 I claim—

1. A winding tube of the character described comprising a conical body having at its larger end a thread-receiving surface continuous with, and extending at an angle inwardly with respect to, the conical external body surface of said tube.

2. A winding tube of the character described comprising a conical body having at its larger end a thread-receiving surface continuous with the external conical surface of

the tube and lying within an imaginary extension of said conical surface.

3. A winding tube of the character described, comprising a conical body having at its larger end a thread-receiving surface continuous with the external conical surface of the tube and oppositely tapered relatively to the latter.

4. A winding tube of the character described comprising a conical body having at both ends thereof thread-receiving surfaces continuous with the external conical surface of the tube and lying within imaginary extensions of said conical surfaces.

ALBERT LINDBERG.
